UNITED STATES PATENT OFFICE

2,346,988

PHOTOGRAPHIC PRINTING APPARATUS

Edward B. Noel, Cleveland Heights, Ohio, assignor
to General Electric Company, a corporation of
New York

Application March 18, 1941, Serial No. 383,975

9 Claims. (Cl. 95—73)

My invention relates to the art of photographic printing, and more particularly to a novel apparatus whereby printing papers may be exposed to light of variable color composition. The invention consists in the new and novel combination of elements hereinafter described and in the method of operating the same.

The recent development of photographic printing papers in which the effects of either soft or hard papers are obtained from a single emulsion by varying the color content of the light used for exposure (Photo Technique, October, 1940, p. 59—Rowland S. Potter) has given rise to a need for a light source in which the relative percentages of the various color components may be varied at will and pre-set at any predetermined desired values before the exposure is made. It is an object of the present invention to provide a printing apparatus incorporating a source of light, the color composition of which may be conveniently and readily varied in the aforesaid manner. Further and other objects and advantages of the invention will be apparent from the following detailed description and from the accompanying drawing in which like numerals indicate like parts throughout and in which Fig. 1 represents apparatus embodying the principles of the invention, while the Fig. 2 represents an alternative modification of the arrangement shown in Fig. 1.

Referring to Fig. 1, the apparatus there shown comprises generally of at least one lamp 10 concentrically surrounded by a rotatable, cylindrical filter 11 which is composed of a pair of semi-cylindrical sections 12 and 13 of different colors. For example, the semi-cylindrical section 12 may be minus blue (a type of yellow filter) and the section 13 minus red (a type of blue filter). After passing through the filter, the light from the lamps 10 goes through the ground glass diffusing plate 14 which renders the illumination on the photographic printing plate or negative 15 uniform. By rotating the cylinders 11 to any desired angular position, the color of the light which passes through the ground glass to the plate 15 may be given any relative percentage composition of the light from sections 12 and 13 varying all the way from 100% minus red when the filter 13 is in the downward position, to 100% minus blue when the filter 12 is in that position. The lamps 10 may consist of any of the sources of white or daylight illumination which are available in the art, or any polychromatic source capable of emitting at least the colors which pass through the filter. For example, they may take the form of an incandescent lamp or a fluorescent gaseous discharge tube of the type shown in the U. S. Patent 2,182,732 to Meyer, et al. The discharge tube in the latter case may be coated with a fluorescent material which produces polychromatic light having the desired colors as components.

Alternatively, the lamps may comprise a clear glass tube in which a gaseous discharge capable of emitting radiation which excites a fluorescent material is operated. In that case, the sections 12 and 13 may comprise semi-cylindrical glass walls upon which fluorescent materials capable of emitting the corresponding colors may be coated.

For the purpose of rotating the members 11 to the desired positions, a gear system indicated generally by the numeral 16 may be provided. The gear system may comprise a series of driving gears 17 which cooperate with the sprockets 18 positioned on the ends of the members 11, a set of idler gears 19 being provided so that the motion of each of the driving gears is in the same direction. The filter members 11 will rotate in the trough formed between the driving gears. The whole system may be rotated by a suitable knob 20 provided on the shaft of the left-hand driving gear 17, the scale 21 being provided for the purpose of calibrating the rotation of the filter members in terms of the color composition of the light reaching the photographic plate. The various members of the system may be supported by any suitable means. For example, the lamps 10 are supported by the bracket 22 and the sockets 23 appended thereto, while the gears 17 and 19 are supported by the bracket indicated generally by the numeral 24. The lamps 10 may be energized by any suitable source of electric power (not shown).

Referring now to the alternative modification shown in Fig. 2, the lamp 10 in this case is housed within a reflector 25 which may be parabolic in form or of any form which will direct the rays of the lamp 10 toward the diffusing plate 14 and the photographic plate 15. The filter members may take the form of the series of interlocking orthogonal vanes 26 and 27, the vanes 26 being of one color such as minus blue, and the vanes 27 of a second color such as minus red. For the purpose of rotating the vanes 26 and 27, a gear system 16a similar to that of Fig. 1 may be provided. Similarly, the knob 20 and the dial 21 may be provided for the purpose of setting the rotation of the vanes and for calibrating the rotation thereof. The operation of the vane system will be generally similar to that of Fig. 1. When the system is rotated to the position shown in the figure, only the minus red vanes 27 will be interposed in the path of the light from the lamp 10, whereas when the system is rotated through approximately 90°, only the minus blue vanes 26 will be interposed in that path. Different percentage compositions of the colors minus blue and minus red may be obtained by rotating the system to the corresponding angular position between these two limits. It will be understood, of course, that the filter 26 may be replaced by a suitably sup-

ported layer of fluorescent material which emits minus blue, while the filter 27 may be similarly replaced by fluorescent material which emits minus red. In this case, the lamp 10 will, of course, take the form of a clear glass discharge tube which emits light capable of exciting the fluorescent material on the vanes.

It will be understood that many modifications of the afore-described system will occur to those skilled in the art to which it appertains. For example, the color filter may comprise more than two colors and the filter members 11 and the vanes 26 and 27 broken into a corresponding number of sections to provide the additional colors. Further, many modifications of the gearing system and the supports may be used. It will also be understood that the described apparatus may be used for either contact printing or for enlarging apparatus. In the latter case, suitable light condensing means may be provided. All such modifications I aim to include within the scope of the appended claims.

What I claim as new and desire to secure by Letters Patent of the United States is:

1. In an apparatus for controlling the color composition of photographic printing light, a source of radiation capable of exciting fluorescent materials, fluorescent means for converting said radiation into either one of at least two separate colors and means associated with said first-mentioned means for causing it to project in a given direction light of only one or the other of said colors or for mixing said primary colors in varying proportions.

2. In an apparatus for controlling the color composition of photographic printing light, a tubular source of radiation capable of exciting fluorescent materials, rotatable tubular members having at least two longitudinally extending sections with fluorescent materials thereon capable of emitting different colors when excited by said radiation surrounding said source, means for rotating said members whereby the relative amounts of said colors in the light output at a predetermined surface in the field of said source may be varied.

3. In an apparatus for controlling the color composition of photographic printing light, a source of radiation capable of exciting fluorescent materials, rotatable members having at least two sections with fluorescent materials thereon capable of emitting different colors when excited by said radiation surrounding said source, means for rotating said members whereby the relative amounts of said colors in the light output at a predetermined surface in the field of said source may be varied from light of either color alone to any desired combination of the two colors, and diffusing means interposed between said rotatable members and said surface whereby the illumination at said surface is rendered uniform.

4. In an apparatus for controlling the color composition of photographic printing light, a photographic plate, a tubular source of radiation capable of exciting fluorescent materials, a rotatable, cylindrical member having longitudinally disposed sections coated with fluorescent materials capable of fluorescing with different colors concentrically surrounding said source and interposed between said source and said plate, diffusing means between said member and said plate, and means for rotating said member whereby the relative amounts of said colors in the illumina-

tion at said diffusing surface may be varied from light of either color alone to any desired combination of the two colors.

5. In an apparatus for controlling the color composition of photographic printing light, a source of polychromatic light, a plurality of filters comprising interlocking rotatable vanes of at least two colors interposed in the path of the rays from said source, means for rotating said vanes whereby the relative amounts of said colors in the light at a predetermined surface in the field of said source may be varied from light of either color alone to any desired combination of the two colors.

10 6. In an apparatus for controlling the color composition of photographic printing light, a photographic plate, a tubular source of polychromatic light, reflector means for directing radiation from said source in the direction of said plate, a plurality of filters comprising interlocking rotatable vanes of at least two colors interposed in the path of said rays, and means for rotating said vanes whereby the relative amounts of said colors in the light impinging upon said photographic plate may be varied from light of either color alone to any desired combination of the two colors.

15 7. In an apparatus for controlling the color composition of photographic printing light, a photographic plate, a source of radiation capable of exciting fluorescent materials, reflector means for directing the radiation from said source in the direction of said plate, a plurality of interlocking rotatable vanes coated with fluorescent materials capable of emitting different colors interposed in the path of said rays, and means for rotating said vanes whereby the relative amounts of said colors in the light impinging upon said photographic plate may be varied from light of either color alone to any desired combination of the two colors.

20 8. In an apparatus for controlling the color composition of photographic printing light, a photographic plate, a tubular source of polychromatic light, reflector means for directing radiation from said source in the direction of said plate, a plurality of filters comprising interlocking rotatable vanes of at least two colors interposed in the path of said rays, and means for rotating said vanes whereby the relative amounts of said colors in the light impinging upon said photographic plate may be varied from light of either color alone to any desired combination of the two colors, and diffusing means for rendering the illumination on said plate uniform interposed between said vanes and said plate.

25 9. In an apparatus for controlling the color composition of photographic printing light, a photographic plate, a source of radiation capable of exciting fluorescent materials, reflector means for directing the radiation from said source in the direction of said plate, a plurality of interlocking rotatable vanes having fluorescent materials capable of emitting different colors interposed in the path of said rays, and means for rotating said vanes whereby the relative amounts of said colors in the light impinging upon said photographic plate may be varied from light of either color alone to any desired combination of the two colors, and diffusing means for rendering the illumination on said plate uniform interposed between said plate and said vanes.

EDWARD B. NOEL.
